UNITED STATES PATENT OFFICE.

CLAUDE J. HERSCHEL, OF ST. JOSEPH, MISSOURI.

NAIL-REMOVER.

1,377,071.

Specification of Letters Patent.

Patented May 3, 1921.

Application filed March 6, 1920. Serial No. 363,897.

To all whom it may concern:

Be it known that I, CLAUDE J. HERSCHEL, a citizen of the United States, residing at St. Joseph, in the county of Buchanan and 5 State of Missouri, have invented certain new and useful Improvements in Nail-Removers, of which the following is a specification.

This invention relates to improvements in nail removers especially adapted for use in 10 removing nails from covers or lids of shipping crates though not necessarily restricted to such use.

An important object of this invention is to provide a nail remover of the class described 15 having novel means whereby all of the nails in one end of a crate cover may be removed simultaneously in a highly convenient and expeditious manner.

A further object of the invention is to 20 provide a nail remover of the class described having means for collecting the nails upon being removed from the crate cover or other length of wood.

A further object of the invention is to 25 provide a device of the class described which is simple in use, neat in appearance and cheap to manufacture.

Other objects and advantages of the invention will be apparent during the course 30 of the following description.

In the accompanying drawing forming a part of this application and in which like numerals are employed to designate like parts throughout the same,

35 Figure 1 is a perspective of the improved nail puller applied to a base.

Fig. 2 is a vertical transverse section through the improved nail puller in use.

In the drawing wherein for the purpose 40 of illustration is shown a preferred embodiment of the invention, the numeral 5 generally designates a bench or other suitable base upon which the improved nail remover, generally designated by the numeral 8, may 45 be rigidly secured.

The improved nail puller forming the subject matter of this application comprises a rectangular box or receptacle having a bottom 10, upstanding side walls 11 and 12 50 and the end walls 13 and 14 which, as illustrated in Fig. 1, are connected to the ends of the side walls 11 and 12. As illustrated in Fig. 2, a length of wood 15 is extended longitudinally of the receptacle and forms 55 what might be termed a cover for the re-

ceptacle. It will be noted, however, that the cover or top 15 of the receptacle is secured to the upper longitudinal edge portion of the side 11, at its ends to the end walls 13 and 14 and is spaced from the upstanding 60 side wall 12 so as to form an entrance opening to the receptacle. The top 15 forms a support for an elongated length of flat sheet metal 18, which is flatly mounted upon the top and is secured at its ends and along one 65 longitudinal edge portion by fastening devices 20 to the side 11 and the end walls 13 and 14. One longitudinal edge portion of the length of flat metal 18 or metallic striking body overhangs the opening to the receptacle and is formed with a plurality of V-shaped teeth 25 which in turn form V-shaped notches 28 which are adapted to receive the shanks of nails 30.

As illustrated in Fig. 1, the portion of 75 said elongated length of flat sheet metal 18 immediately rearwardly of said teeth 25 is secured to the adjacent portion of the cover or top 15 by fastening devices 32. In this manner the teeth 25 are rendered extremely 80 rigid and are therefore enabled to withstand great strain in use. In the use of the device for removing nails from covers of egg crates and other shipping cases, the forward ends of the nails extended through the end 85 portion of the crate cover are struck smartly upon the elongated length of sheet metal 18 so as to space the heads of the nails upwardly from the adjacent side of the crate cover. With the heads of the nails thus 90 spaced upwardly from the adjacent side of the crate cover, the shanks of the nails are inserted into the notches 28 by a rearward movement of the crate cover. The rear portion of the crate cover may now be moved 95 downwardly by employing the upper edge of the side 11 as a fulcrum so that the heads of the nails are engaged with the under sides of the teeth 25. By a further downward movement of the rear end of the crate 100 cover, designated by the numeral 35, the nails 30 may be entirely removed from the crate cover. Upon being removed from the crate cover, the nails drop into the receptacle and are thereby collected and prevented 105 from being scattered about the floor.

The nails thus removed from the crate cover are not in any way bent or weakened and may therefore be used again. It will be noted also that by properly using the device 110

the crate or the cover is not damaged and may be employed again.

The fastening devices 32 extended through one edge portion of the elongated sheet of metal 18 serve to strengthen the top 15 so that the same is prevented from becoming loosened as the result of continued striking of the nails against the same.

When the nails have been removed from 10 all of the crate covers, the fastening devices 40 employed for securing the receptacle to a base may be removed and the device placed out of the way until it is desired to use the same again.

15 It is to be understood that the form of the invention herewith shown and described is to be taken as a preferred embodiment of the same and that such minor changes in construction and arrangement of parts may 20 be made as will remain within the spirit of the invention and the scope of what is claimed.

Having thus described the invention, what is claimed as new is:—

25 1. A nail remover comprising a flat sheet of metal having a plurality of notches along one longitudinal edge for receiving the shanks of nails, the other longitudinal edge portion of said sheet of metal being adapted 30 for use as a fulcrum and a support for said flat sheet of metal.

2. A nail remover comprising a flat body having a plurality of V-shaped notches extending out through one edge thereof, and 35 a receptacle arranged beneath and supporting said body for receiving the nails removed by contact with the under side of said body.

3. A device for removing nails from 40 shipping case covers comprising a receptacle, a flat length of sheet metal secured to the top of said receptacle and provided along one longitudinal edge with a plurality of V-shaped teeth thereby forming notches, one 45 longitudinal edge of said length of sheet metal being adapted for use as a fulcrum.

4. A device for removing the nails from 50 crate covers comprising a receptacle having a top flush with the upper side of the same and spaced from one longitudinal edge of 55 the same, a metallic striking body flatly secured to said top and to the sides and ends of said receptacle, one longitudinal edge portion of said metallic striking body being extended beyond the adjacent longitudinal edge of said top and provided with a plurality of V-shaped teeth adapted for engaging 60 nails extended through the crate covers, one longitudinal edge portion of said metal-

lic striking body being adapted for use as a fulcrum for the crate covers.

5. A device of the class described comprising a receptacle inclusive of side and end walls and a top connected to one of the side walls and said end walls, the upper side 65 of said top being flush with the upper edges of said side and end walls, a metallic striking body flatly mounted upon said top, and the adjacent portions of said end walls and one of said side walls, fastening devices 70 rigidly connecting said metallic striking body to the adjacent portions of said end walls and one of said side walls, one longitudinal edge of said top being spaced from the opposed side of said receptacle thereby 75 forming an opening, one longitudinal edge portion of said metallic striking body being extended over said opening and provided with a plurality of V-shaped teeth thereby forming nail receiving notches, and fastening devices extending through said metallic striking body rearwardly of said teeth for connecting the striking body to the adjacent longitudinal edge portion of said top.

6. A device for removing nails from 80 bodies comprising a flat striking body having one edge portion provided with nail gripping means.

7. A device for removing nails from 85 bodies comprising a flat striking body having one edge portion provided with nail gripping means, and a supporting device 90 for said body.

8. A device for removing nails from 95 bodies comprising a flat striking body having one edge portion provided with nail gripping means, and a supporting device for said body, said supporting device being spaced from said nail gripping means.

9. A device for removing nails from 100 bodies comprising a flat metallic striking body adapted to be engaged by the nails and provided along one edge portion with a plurality of nail gripping teeth, the opposite edge portion of the body being adapted for 105 use as a fulcrum.

10. A device for removing nails from 110 bodies comprising a flat metallic striking body adapted to be engaged by the nails and provided along one edge portion with a plurality of nail gripping teeth, the opposite edge portion of the body being adapted for use as a fulcrum, and a supporting device 115 for said striking body provided with means for receiving the nails.

In testimony whereof I affix my signature.

CLAUDE J. HERSCHEL.
